UNITED STATES PATENT OFFICE

91,363

DESIGN FOR A BOTTLE

Clement S. McPhee, Cranston, R. I., assignor to Everett & Barron Company, Providence, R. I.

Application August 5, 1933. Serial No. 48,932

Term of patent 7 years

To all whom it may concern:

Be it known that I, CLEMENT S. MCPHEE, a citizen of the United States, residing at Cranston, in the county of Providence and State of Rhode Island, have invented a new, original, and ornamental Design for a Bottle, of which the following is a specification, reference being had to the accompanying drawing forming part thereof.

The figure is a perspective view of a bottle showing my new design.

I claim:

The ornamental design for a bottle, as shown.

CLEMENT S. MCPHEE.
